Primary Examiner — Eric L Goodman*Assistant Examiner* — Sarah L Smith(74) *Attorney, Agent, or Firm* — Lee & Hayes, P.C.(57) **CLAIM**

The ornamental design for a candle assembly drain, as shown and described.

DESCRIPTION

FIG. 1 is a top perspective view of a candle assembly drain. FIG. 2 is a bottom perspective view thereof.

FIG. 3 is a front view thereof.

FIG. 4 is a back view thereof.

FIG. 5 is a left-side view thereof.

FIG. 6 is a right-side view thereof.

FIG. 7 is a top view thereof.

FIG. 8 is a bottom view thereof.

FIG. 9 is a bottom perspective view of the candle assembly drain showing unclaimed environment (i.e., a base and a mold) of the candle assembly drain; and,

FIG. 10 is a top perspective view thereof showing unclaimed environment (i.e., a base, a tea candle, and an ice mold) of the candle assembly drain.

The broken lines in FIGS. 1-10 depict portions of the candle assembly drain and in FIGS. 9 and 10 additional broken lines depict environment. All broken lines form no part of the claimed design.

1 Claim, 10 Drawing Sheets
